Specification of Letters Patent. Patented July 14, 1914.

Application filed August 12, 1912. Serial No. 714,534.

To all whom it may concern:

Be it known that I, ALEXANDER W. FINLAYSON, a citizen of the United States, residing at Detroit, in the county of Wayne, State of Michigan, have invented certain new and useful Improvements in Heaters; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to heaters, especially designed for heating dwellings, and consists in the construction and arrangement of parts hereinafter more fully set forth and pointed out particularly in the claims.

The object of the invention is to provide a heater of the character described of simple, compact and comparatively inexpensive construction, wherein, in a hot water heater, the return water is directed over the fire before again entering the circulatory pipes, and wherein, in a steam generator, a circulation of water between the upper water head and the hollow base is maintained.

The invention contemplates an arrangement for assembling the heating pipes in independent units, so disposed and having such connection with the structure as to enable the removal of any section without disturbing the other sections of the heater.

The above object is attained by the apparatus illustrated in the accompanying drawings, in which:—

Figure 1 is a fragmentary view partly in vertical section of a heater embodying my invention. Fig. 2 is a horizontal section as on line 2—2 of Fig. 1. Fig. 3 is an enlarged fragmentary view in section, showing the manner of making the connection between the heads of one of the heating units through the medium of tapered connecting pipes which are drawn into beveled apertures in said heads by hollow tie-bolts, through which the hot gases from the combustion chamber circulate. Fig. 4 is a fragmentary view in horizontal section through the base. Fig. 5 is a vertical section through the heater in a plane substantially at right-

angles to Fig. 1. Fig. 6 is an enlarged transverse section through the pipes of one of the heating units as on line 6—6 of Fig. 5. Fig. 7 is a plan view of a hollow cast receptacle affording therein a chamber for the separation of the steam and water when the device is used as a steam heater. Fig. 8 is an enlarged fragmentary view of one of the heating units. Fig. 9 is an inverted plan of a hollow casting forming within it a chamber which serves as a steam dome and through which is a central aperture for the passage of the flue gases.

Referring to the drawings by the characters of reference marked thereon, 1 designates a quadrangular base cast hollow in two sections, said sections being connected through the medium of tapered nipples 2, which are drawn into beveled apertures in the connected ends of said sections by means of transverse tie-bolts 3, which pass through the hollow sections of the base and through said nipples, receiving on their ends the binding nuts 4, as clearly shown in Figs. 2 and 4. Within the hollow base is fitted the grate, not shown, which, in conjunction with the surrounding walls of the base, forms the fire-pot of the heater.

Projecting vertically from two sides of the base are the pipes 5 which have long threads 6 upon their lower ends (see Fig. 5) that screw through tapped apertures in said base. Upon said pipes are the jam nuts 7. The upper end of each of the pipes 5 is threaded to screw into a tapped aperture in the bottom of the lower head 8 of each of the heating units, the long threads 6 on the lower ends of said pipes 5 enabling them to be screwed from the base into said heads without disconnecting them from the base. The heating units comprise the hollow lower head 8, the hollow upper head 9 and the vertical pipes 10 extending between and connecting said heads. These pipes 10, as will be seen by referring to Fig. 3, are provided with tapered ends 11, which fit into beveled apertures in the walls of said heads and into which they are drawn to effect a tight joint by means of hollow connecting rods 12, which pass through said heads and through said pipes, receiving on their projecting ends the nuts 13, which screw thereonto and bear against copper washers 14 lying upon the

faces of said heads. By this arrangement the heads of the heating units are connected to effect a circulation of water between them in a manner to obviate the use of threads 5 where they will be subjected to the action of the fire, and in a manner to afford a circulating passage for the hot gases through the hollow connecting rods 12, thereby materially adding to the heating surface of the 10 heater. The lower ends of the hollow connecting rods 12 stand over the fire space in a position to receive the products of combustion directly from the combustion chamber.

15 Extending centrally from each of the upper heads 9 is a connecting pipe 15 which communicates with the receptacle 16 through the bottom thereof, and which is provided with tapered ends that are drawn into beveled apertures in said connected parts by a 20 hollow connecting rod 17, which passes through the head 9, the pipe 15 and through the hollow receptacle 16 and receives upon each of its threaded ends a nut 18, through 25 the medium of which the hollow receptacle and head 9 are drawn together to effect a tight joint between them and the tapered ends of the pipe 15.

The hollow connecting rods 17 afford a 30 passage for the products of combustion through the upper heads 9, the pipes 15 and the hollow receptacle 16, said gases impinging upon the under side of the hollow steam dome 19, which is disposed above the hollow 35 member 16.

It will now be apparent that the heating 40 sections comprise the lower and upper heads 8 and 9 connected by the vertical pipes 10, and that each section or unit is connected with the hollow base through a pipe 5, and 45 with the receptacle affording the separating chamber through a pipe 15. By this arrangement, the sections or units are made independent of one another, enabling each 50 heating unit to be disconnected and removed from the heater without disturbing the other sections or units. It will also be apparent from the arrangement shown and described that an extensive heating surface is afforded 55 by reason of the exterior surface of the hollow heads and connecting pipes, and by the interior surfaces afforded by the hollow connecting rods 12 and 17.

To connect the steam dome 19 with the 60 hollow member 16 affording the separating chamber, there are employed a number of pipes 20 having tapered ends which are drawn into beveled apertures in the parts 65 21, which pass through said chamber and dome and through said pipes, receiving on their upper ends the nuts 22. Through the pipes 20, the steam which separates from the water within the separating chamber 70 passes into the steam dome 19. Through the

hollow dome 19 is a central opening 23 into which the flue gases are directed and which pass to the stack through the pipe 24.

Leading from the steam dome 19 are the circulatory pipes 25 which are connected with the radiators of the heating system, not shown. The return pipes from the radiating system connect with the hollow base as shown at 26 in Fig. 2.

Where the apparatus is used as a steam generator, a connection between the separating chamber and the hollow base is effected by means of the vertical pipes 27 whose upper and lower ends are connected respectively with the separating chamber and the base through the medium of the tapered nipples 28, as shown in Fig. 1, and the tie-bolts 29 which pass through the elbows 30 of said pipes, through the nipples 28 and through the walls of the base and of the 35 separating chamber, said bolts receiving on their ends the nuts 31.

The hollow casting 16 which affords the separating chamber is provided at opposite margins with the hollow projections 32, as 90 shown in Fig. 7. It is through the wall of one of these hollow projections that the bolts 29 pass to connect the upper ends of the pipes 27 with the separating chamber, as shown at the top of Fig. 1.

Where the apparatus is used as a hot water heater, the pipes 27 are dispensed with and the whole system is filled with water, as will be well understood.

To increase the heating area through the separating chamber 16, openings 33 are formed therethrough (see Fig. 7) that allow the passage of the products of combustion.

To distribute the products of combustion against the under side of the steam dome 19, baffle plates 34 are disposed between the lower and upper faces respectively of the separating chamber and the steam dome, which cause the products of combustion passing upwardly through the openings 35 110 between the projections 32 of the hollow member 16 to pass around the ends of the baffle plates before entering the smoke pipe 24.

Having thus fully set forth my invention, 115 what I claim as new and desire to secure by Letters Patent is:—

1. In a heater, the combination with a hollow base and a hollow member disposed above the base, of a series of independent heating units, comprising hollow heads, pipes connecting said heads having tapered ends drawn into beveled apertures in said heads, hollow connecting rods passing through the heads and through said pipes and engaging said heads, a threaded pipe connecting the lower head of each heating unit with the base, a pipe connecting the upper head of each heating unit with said hollow member, a hollow connecting rod passing through said pipe, the 130

upper head and said hollow member and engaging said members to detachably connect said parts and afford interior communication and an exterior passage through said connecting parts.

2. In a heater, the combination of a hollow base, a receptacle above the base, heating units interposed between the base and receptacle, each unit comprising upper and lower heads, pipe sections having tapered ends seated in beveled apertures in said heads to connect them, and hollow tie bolts passing through said heads and through said connecting pipes, a pipe detachably connecting the upper head of each unit with the upper receptacle, and a pipe detachably connecting the lower head of each unit with the hollow base.
3. In a heater, the combination of a hollow base, heating units comprising upper and lower heads connected by pipes, the lower heads of said units being connected with said base, a hollow member above said heating units, a pipe connecting the upper head of each heating unit with said hollow member, and hollow rods engaging with the upper

heads of the heating units and said hollow member passing therethrough and through said connecting pipes to tie said parts together and afford a passage for the caloric current therethrough.

4. A heater unit comprising upper and lower hollow heads, a plurality of apertures extending through the walls of said heads, the walls of the apertures of the opposed heads having beveled edges, pipes having tapered ends seated in said beveled edge apertures, hollow tie rods passing through said pipes and heads and having exterior threaded ends, threaded nuts on the ends of said tie rods engaging the outer walls of said heads for drawing said parts together to effect an interior communication between said pipes and heads, and an exterior communication with said heads through said tie rods.

In testimony whereof, I sign this specification in the presence of two witnesses.

ALEXANDER W. FINLAYSON.
